2,397,080

APPLICATOR FOR ADHESIVES

Franklin B. Baker, Chicago, Ill.

Application March 19, 1943, Serial No. 479,707

2 Claims. (Cl. 15—140.3)

This invention relates to improvements in adhesive applicators.

Various distinctly different types of applicators are required for many different conditions of use. Among them are applicators which can be kept immersed in a paste or mucilage jar between periods of use, and it is this type with which this invention is concerned. In the applicator which I have heretofore devised, a rigid wooden stem is secured by a tack to the inner surface of a bottle cap and a thin sheet of flexible rubber is secured to the lower end of the wooden stem to serve as the spreader for the adhesive.

I have now devised a new form of applicator which I consider an improvement in certain respects over my prior applicator. In this improved form of applicator I use a rigid wooden stem firmly secured to the bottle cap, as in my prior invention, but the adhesive spreader is supported on the wooden stem by means of a rubber boot having the spreader formed integrally therewith or attached thereto. The boot not only serves to connect the applicator to the stem, but at the same time, protects the stem from contact with the adhesive, thus avoiding any reaction between the adhesive and any resin, sap or other substances in the wood capable of harmfully reacting with the adhesive to give it an undesirable odor or color, or which might cause objectionable reactions on the wood itself.

In accordance with this invention, I employ a wooden stem having a squared upper end attached to the inside surface of the cap by an ordinary flat-headed tack, and over this stem I draw a moulded rubber boot having a flexible spreader at its lower end. The boot extends upwardly above the level of the adhesive to the inner surface of the cap and hence no contact between the wooden stem and adhesive can take place. The stem of this applicator is rigid and only the flexible spreader at the lower end is deflected when the user is holding the applicator by means of the cap. At the same time, the simple, inexpensive and wholly satisfactory method of attaching the stem to the cap is made possible by the use of a wooden stem inside of the rubber boot. The visible portion of the applicator member being entirely of rubber, the appearance of the device is also enhanced thereby.

In this form of applicator the bottle cap may be used as the handle of the device and a rigid wooden stem enables the user to direct the movements of the applicator very accurately in the area in which the adhesive is to be applied.

The attainment of these advantages in this new

form of applicator, as well as other advantages, comprise the objects of this invention.

Another advantage of this new applicator resides in the fact that I am able to produce a completely satisfactory applicator at extremely low cost and thus make its advantages available to the public at a price within the reach of even those with whom thrift is a matter of necessity instead of choice.

10 The accompanying drawing shows a preferred form of the invention which will serve to illustrate the manner in which the invention may be constructed and used.

Referring now to the drawing:

15 Fig. 1 is a central vertical sectional view showing the applicator attached to a cap and positioned in its normal relation to an adhesive bottle.

Fig. 2 is an elevation of the cap and applicator from a position at right angles to the position 20 of Fig. 1.

Fig. 3 is an elevation showing the applicator in use.

Referring further to the drawing, the applicator consists of a rigid wooden stem 1 having its upper end cut off square and held snugly against the usual paper liner 2 of the cap 3 by means of a flat-headed tack 4 driven through the cap. The rubber portion of the device consists of the boot 5 snugly surrounding the stem and held thereon by a snug fit, the lower end of the device being moulded to form a fin 6 which merges into the moulded boot as shown in the drawing.

This moulded product does not require the use of stock made wholly of new rubber. Hence, 35 through the use of some scrap, the cost of the rubber portion of the device is kept low. Yet, because of the rigid wooden stem, its rigid attachment to the cap, and the moulded relationship between the fin and the boot, the user is able

40 to maintain accurate control over the manipulation of the fin. This may be contrasted with the difficulties which would be encountered through the use of a solid moulded stem and applicator, it being obvious that if the wooden stem were supplanted by a wholly moulded rubber stem the whole device would have a flexibility and snap which would render it too difficult for one to use accurately. Thus, by providing an applicator 45 capable of accurate control the user will be able to apply a uniform downward pressure and will be able to apply accurately a film of desired thickness.

In order to attain the firmest control over the fin at the lower end of the rubber boot I so mould 50 the interior of the boot and shape the exterior of

the stem that they fit together snugly at the lower end of the stem. As shown, the lower end of the stem may be provided with an inwardly tapered surface 7 and a squared lower end 8, both of which snugly fit the bottom recess in the boot. The ribs 9 and 11 extend upwardly from the fin and, merging into the body of the boot, cooperate with the stem in assuring firm control over the spreading fin. Hence, the user may accurately control both the direction and uniformity of the spreading of the film of adhesive.

In view of the fact that when the device is in use it will often be rested temporarily bottom side up on the cap, and adhesive, if a surplus is on the stem, may flow down toward the cap, I prefer to draw the boot snugly up against the liner 2 in order that the adhesive may not contact the wooden stem, even to a limited extent. Should the applicator be left out of the bottle inadvertently and adhesive accumulate and dry thereon, the continuous rubber boot makes it easy for the dried adhesive to be scraped or washed off.

Of course, in using the term "rubber" I mean to include not only the rubber of nature, but also the synthetic rubber substitutes which have recently become commercially available.

It will be further noted that not only does this present invention make available the advantages of the rigid wooden stem which can be cheaply secured to the bottle cap, but no special treatment or selection of the wood is required, which I find is of substantial advantage in these days when imperfectly dried or weathered wood stock is the most commonly available supply.

While my applicator is especially adapted to the spreading of semi-fluid and liquid adhesive, it may be employed for the spreading of paste adhesives, and if desired, for the spreading of other materials. Also the shape of the applicator at the bottom of the stem may be modified and the manner of its union with the rubber boot may be altered. In any event, the rigid wooden stem affords proper control over the applicator which is itself remote from the bottle cap, while the boot which connects the applicator element to the rigid stem also protects the wooden stem from any harmful or unsightly reaction with the adhesive.

In my prior application Serial No. 271,054, filed May 1, 1939 now Patent 2,291,676 dated Aug. 4, 1942, I have shown an applicator which includes the bottle cap with wooden stem attached thereto.

It should be understood, therefore, that this invention is susceptible of considerable variation without departing from the spirit of the invention as defined in the following claims.

5 Having shown and described my invention, I claim:

1. In combination, an adhesive container, a flat-topped cover member therefor, cooperating means on the container and cover for sealing the 10 container by means of the cover, a rigid wooden stem having its upper end squared and extending perpendicularly from the underside of the cover member into proximity with the bottom of the container, a flat-headed nail piercing the cover member and the squared end of said stem to secure the latter firmly against the cover, and a rubber boot snugly surrounding the entire length of 15 said stem from the underside of the cover to the lower end of the stem and having its lower end protruding below the lower end of the stem to the bottom of the container and fashioned in the form of a flexible fin for spreading adhesive, the cover when removed serving as the gripping means for 20 the adhesive spreader, and when inverted to stand on its top, serving to hold the spreader in a substantially erect balanced position.

2. In combination, an adhesive container, a flat-topped cover member therefor, cooperating means on the container and cover for sealing the 30 container by means of the cover, a relatively thick rigid wooden stem having its upper end squared and extending perpendicularly from the underside of the cover member into proximity with the bottom of the container, a flat-headed nail piercing the cover member and the squared end of said stem to secure the latter firmly against the cover, and a moulded rubber element having a relatively thin-walled hollow boot portion snugly 35 surrounding the stem from the underside of the cover to its lower end and having a portion tapering abruptly immediately below the lower end of the stem to form a thin flexible fin extending to the bottom of the container for spreading adhesive, the lowermost portion of the stem being reduced in diameter to extend snugly into the tapered portion of the rubber element, the cover when removed serving as the gripping means for 40 the adhesive spreader, and when inverted to stand on its top, serving to hold the spreader in a substantially erect balanced position.
